UNITED STATES PATENT OFFICE.

THEODORE L. VALERIUS AND OLAF LARSEN, OF FORT ATKINSON, WISCONSIN, ASSIGNEES TO THE CREAMERY PACKAGE MFG. COMPANY, OF CHICAGO, ILLINOIS, A CORPORATION OF ILLINOIS.

APPARATUS FOR CLEANING AND DRYING ICE-CREAM BRICK MOLDS.

Application filed September 1, 1921, Serial No. 497,751.

To all whom it may concern:

Be it known that we, THEODORE L. VALERIUS and OLAF LARSEN, citizens of the United States, residing at Fort Atkinson, 5 in the county of Jefferson and State of Wisconsin, have invented certain new and useful Improvements in Apparatus for Cleaning and Drying Ice-Cream Brick Molds, of which the following is a specification.

10 Our invention relates to means for washing, draining, sterilizing and drying in a thorough, convenient, sanitary and rapid manner, the metallic molds or pans in which ice cream intended for sale in the form of 15 bricks, slices or cubes, is frozen.

The object of our invention is to produce an apparatus which can be conveniently controlled by one man and in which the molds or pans to be treated are passed in a 20 continuous row, first through a washing field, then through a draining field, and then through a drying field, to be delivered in a clean, dry and sanitary condition ready to be filled with cream.

25 The utility of our apparatus will become apparent from the following specification, and the accompanying drawings in which a construction incorporating the various features of our invention is shown and on 30 which:

Fig. 1^a is a side elevational view of the left half of the apparatus,

Fig. 1^b is a side elevational view of the right half of the apparatus,

35 Fig. 2 is an enlarged view from plane 2-2, Fig. 1^a,

Fig. 3 is a plan view of one end of the washing section,

40 Fig. 4 is a plan view showing the guiding means for changing the positions of the molds when traveling from the draining section to the drying section,

Fig. 5 is a sectional view on plane 5-5, Fig. 4,

45 Fig. 6 is an enlarged sectional view on plane 6-6, Fig. 1^b, and

Fig. 7 is an end view of the entrance end of the apparatus.

The apparatus comprises the entrance section E, the washing section W, the draining section D, and the drying section H. At the 50 washing section is provided the supporting structure comprising the rectangular frame 10 mounted on legs 11. Secured to and ris-

ing from the legs 11 at the ends of the frame 55 10 are standards 12 and 13 of rectangular shape which are connected together at their upper corners by angle bars 14. A cover 15 extends between the tops of the standards and removable side walls 16 and 17 form 60 65 with the cover a chamber in which the molds are washed. Extending from the opposite sides of each standard are the brackets 18 and 19 of L-shape for supporting respectively the mold bodies B and their covers C. 65 The bases of the brackets incline downwardly and the upright members thereof incline inwardly and engage at their upper ends as clearly shown in Fig. 2, the base members of the bracket 18 being longer than 70 75 those of the bracket 19 in order to accommodate the larger body parts of the molds. The brackets 18 are connected by a floor plate 20 and the brackets 19 are connected by a floor plate 21 on which floor plates the 75 body and cover parts, respectively, rest while traveling through the washing field. The upright parts of the brackets are connected respectively by bars 22 and 23 against which the open sides of the body and cover parts 80 85 lean, the interior of the body and cover parts being thus exposed to receive washing water and to readily discharge the washing water owing to the inclined position of the supporting brackets.

Above the brackets the standards support arches 25 between which extend the guide bars 26 for preventing tipping of the body and cover parts of the molds out of their inclined positions on the supporting brackets. 90

The entrance section E of the apparatus is formed of the walls 27 and 28 which have the same inclination as the upright sections of the brackets 18 and 19, and lead thereto. 95 The walls at their lower ends are bent to form the troughs 29 and 30 for receiving the lower ends of the body and cover parts of the molds, the floors of the troughs being inclined and leading to the floor plates 20 and 21 of the bracket members in the washing field. The body and cover parts are set on edge in the troughs and rest in inclined position against the walls 27 and 28, and the mold parts are then pushed into the washing field in a continuous row.

Extending longitudinally through the washing section housing between the bracket frames therein is the spray or jet pipe 31,

and extending through the upper part of the housing above the mold parts therein are the jet pipes 32 and 33. These jet pipes are connected by branch piping 34 and 35 with the main piping 36 connected with the pump 37 which is driven by a motor M. Below the washing field the tank 38 is suspended from the frame 10 and is connected by pipes 39 with the inlet end of the pump 37. The water for washing the mold parts is thus drawn from the tank and jetted or sprayed over the parts, from which it flows back into the tank. Fresh water may be supplied through the pipe 40 and steam through the pipe 41. Before using the apparatus, water and steam are charged into the tank until the water is at the desired temperature. The same water may then be used for a period of washing and, if desired, there may be a continuous inflow of steam and water, the overflow pipe 41^a being provided for the tank which keeps the water from rising above a certain level and through which scum and dirt floating on the water may escape. The pump delivers the cleaning water to the jet pipes under considerable pressure and the jets are directed with considerable force against the insides of the mold parts and the outsides thereof, the molds being thus thoroughly washed. In the form of mold shown the body part has the cover receiving bead or flange *b* and the cover part has the peripheral flange *c* for engaging with the bead. These flanges engage the floor plates and hold the lower sides of the body and cover away from the plates so that the washing water can readily flow along and clean the bottom sides of the parts.

The jet pipes may be supported in any convenient way in the washing section housing. As shown they are supported in the end walls 42 which close the ends of the housing except for the spaces between the brackets and the arches.

The draining section D forms a continuation of the washing section, and has the floor plates 43 and 44 forming a continuation of the floor plates in the washing section, the bars 45 and 46 forming continuations of the bars 22 and 23 of the washing section, so that the body and cover parts of the molds pass through the drain section in the same position as in the washing section to permit the water to drain from the inside and outside thereof, the drain section being preferably enclosed and having the bottom 47 along which the drain water flows back into the tank 38.

After passing through the drain section the mold parts reach the dryer section H. The dryer section is mounted on pedestals 48 and comprises the outer framework 49 (Fig. 6) containing the W-shaped guide trough 50 having the outwardly inclined

side walls 51 and 52 and the upwardly inclined base walls 53 and 54 on which the body and cover parts, respectively, of the molds are supported, the body parts resting with their bottoms against the wall 50 and with their flanges against the wall 53, and the cover parts resting with their tops against the wall 52 and with their flanges against the wall 54. In order to tip the mold parts to their new positions in the dryer field, as shown in Fig. 5, the upper guide bars 45 and 46 coming from the drain section diverge a sufficient distance, as indicated at 45', 46' in Fig. 4, to cause the body and cover parts to be tipped from their positions in the drain section to their new positions in the dryer section.

We preferably utilize electrical means for providing the necessary heat in the dryer section. As shown, electrical heating elements 55 are supported against the rear sides of the walls 51 and 52 so that the heat is applied to the bottoms of the body and cover parts to produce rapid evaporation of any moisture within these parts and to quickly dry them. Suitable switch mechanism 56 is provided for controlling the electrical circuit for the heating elements.

The apparatus can be readily taken care of by one man, who inserts the mold parts at the entrance end and in so doing pushes along the molds and covers previously inserted. In the washing field the parts are thoroughly washed and rinsed, and in the draining field the water rapidly drains from the parts, and they will also be dried to a considerable extent owing to the heating they receive while in the washing section. After leaving the draining section the mold parts are automatically tipped over against their backs and the heat which they receive thoroughly dries them. The application of the hot water to the mold parts and the heating thereof during passage through the driving section causes the parts to be thoroughly sterilized, and when the parts are delivered from the apparatus they are clean and sanitary and ready to be filled with cream. As the washing and draining sections are entirely enclosed, the surroundings may be kept in dry and sanitary condition. With our apparatus there is also no wastage of water, as only sufficient fresh water is added to compensate for the dirty water which flows off through the drain pipe 42 from the tank.

We do not desire to be limited to the exact construction, arrangement and operation shown and described, as changes and modifications could be made which would still come within the scope of our invention.

We claim as our invention:

1. In an apparatus of the class described, the combination of a continuous guideway along which the body and cover parts of

- ice cream brick molds may be shifted in separate rows, water jet pipes extending along a section of said guideway for directing water jets to said mold parts, said guideway comprising means to support said parts in inclined position with their open sides down to receive the water on the inside and outside when traveling past said jet pipes and to discharge the cleaning water, heating elements arranged along another section of said guideway to form a heating field, and means for automatically tipping said mold parts before reaching the heating field whereby they are inclined with their open sides up while being dried.
2. In an apparatus of the class described, the combination of opposed guide members along which the body and cover parts of ice cream brick molds may respectively be shifted, jet pipes adjacent a section of said guide members, said members at said section being inclined and the body and cover parts resting with their open sides against said members whereby cleaning water will be discharged therefrom, said members at a succeeding section being inclined in the opposite direction to support the closed sides of the body and cover parts, means for automatically tipping said parts during their travel from one of said sections to the other, and means for heating said parts when in the last named position.
3. In an apparatus of the class described, the combination of a supporting guideway along which the body and cover parts of ice cream brick molds may be shifted in separate rows, a portion of said guideway being adapted to support said parts with their closed sides up, means for applying cleaning water interiorly and exteriorly of the parts when in this position, means for automatically tipping said parts while traveling over another portion of said guideway to bring them into position with their closed sides down, and means for heating said parts when in this latter position.
4. In an apparatus of the class described, the combination of a continuous guideway along which the body and cover parts of ice cream brick molds may be shifted, water jet pipes arranged along a section of said guideway, said guideway comprising means for supporting the mold parts on edge with their open sides inclined downwardly when traveling past said jet pipes whereby said parts will be washed inside and outside, means for producing heat along another section of said guideway, said guideway having means for tipping the mold parts before reaching said heating section to position said parts with their open sides inclined upwardly.
5. In an apparatus of the class described in combination, a continuous guideway along which the body and cover parts of ice cream brick molds may be shifted in separate adjacent rows, said guideway having a portion comprising under supports for said body and cover parts and inner lateral guide bars adapted to retain said parts in inclined position with their open sides down, means for washing said parts while in such position, said guideway having another portion continuous with said first portion comprising under supports for said parts and outer lateral guide walls adapted to retain said parts in inclined position with their open sides up, said inner lateral guide bars extending divergently into said second portion of said guideway to tip said parts laterally outward upon said guide walls, and means for heating said guide walls.

In testimony whereof we have hereunto set our hands.

THEODORE L. VALERIUS.
OLAF LARSEN.
